AUTOMATIC STOKER

Weston M. Fulton, Knoxville, Tenn., assignor to
 W. J. Savage Company, Inc., Knoxville, Tenn., a
 corporation of Delaware

Application September 9, 1931, Serial No. 561,911
 Renewed January 4, 1938

29 Claims. (Cl. 110—30)

This invention relates to heating plants, and more particularly to automatic stokers for burning solid fuel.

It has previously been proposed to provide furnaces burning solid fuel, such as coal or coke, with fuel magazines or hoppers which, as long as they are kept supplied with fuel, provide a continuous, gravity feed of fuel to a burning zone within the furnace to which air is admitted by the usual dampers and through suitable tuyères, the ashes being deposited in an ash pit within the furnace whence they may be removed manually. Other stokers have also been provided wherein the fuel is fed mechanically, as by a moving grate or a screw conveyor, and combustion is facilitated by a power driven air blower. Still other forms of automatic heating plants have been suggested wherein fuel is supplied from a magazine and mechanically fed into a burning chamber, air being supplied under pressure to said chamber through tuyère blocks supporting the fuel bed, and suitable automatic temperature responsive control devices being provided for controlling the supply of current to the motor which actuates both the fuel feeder and the air blower.

All of these prior devices, however, possess objectionable features which it is the object of the present invention to overcome. The earlier type gravity feed magazine furnaces were particularly objectionable because irregular holes or cavities would burn through the fuel causing it to arch over the cavities and fail to feed downwardly, and there was also often a tendency for smoke to pass upward through the magazine and escape around the edges of the magazine door, this being especially true when the fuel had fed down low in the magazine to a point where the thickness of the fuel above the burning zone was very slight. Other difficulties experienced with this type of furnace included the escape of volatile matter from the fuel and its deposit on and around the magazine door, the clogging of the burning zone with ashes due to failure to remove them at proper intervals, the necessity for a strong chimney draft, and the limitation in capacity of the fuel magazine to the size of the furnace since the former was provided as an integral part of the latter.

Similarly, the power driven stokers heretofore known have also been subject to various objections, including some of those mentioned in connection with the gravity feed type. For example, great difficulty has hitherto been experienced in maintaining a burning zone or fire bed of uniform thickness, this resulting in wide fluctuations in

the efficiency at which the fuel is burned. When the demand upon the stoker is great, the tendency is for fuel to accumulate in the burner to a depth which is too great to permit of complete combustion. On the other hand, when the demand is slight, the fuel bed has a tendency to become so thin that the amount of air passing through it is greater than can be consumed by the fuel, and causes a cooling effect with consequent loss of heat units. Secondly, in these automatic stokers of the prior art the combustion chamber and tuyères are located in the fire box of the furnace or heater itself which makes it difficult to remove the ashes and clinkers, and also increases the tendency for fine ash to accumulate in the flues and smoke pipes of the furnace. Thirdly, the tuyères around the combustion chamber are dependent entirely upon the incoming air to cool them below the fusing point with the result that if the combustion chamber becomes accidentally clogged, or if the air supply is insufficient, the tuyère blocks are often burned out. Fourthly, feeding mechanisms previously known have often-times become clogged by oversize pieces of fuel or other foreign matter, such clogging resulting either in a breakage of some of the parts or in the temporary stoppage of the stoker. Still another serious difficulty which has hitherto been encountered with stoking devices has resulted from a persistent tendency of the coal or other fuel to bridge or arch at the discharge outlet of the hopper. When this arching occurs, no further fuel feeds down into the combustion chamber or conveyor until the arch is broken up.

It is therefore one of the objects of the present invention to provide an automatic stoker for solid fuels which is certain and efficient in operation, simple and rugged in structure, and free from the defects common to devices of this character previously known to the art.

Another object is to provide a combined automatic stoker and furnace for a heating system which includes a combustion chamber and ash disposal means which are entirely disposed outside of the fire box of the ordinary furnace or boiler, and which can be readily connected to any existing heating plant with a minimum of reconstruction and rearrangement work.

A further object is to provide a combined automatic stoker and furnace wherein the fuel bed is continuously maintained at a predetermined thickness and air is supplied thereto under pressure on the cross draft principle.

Still another object is to provide an automatic stoker embodying novel feeding mechanism for

continuously agitating the fuel bed and moving it so as to prevent irregular burning and arching of the fuel, together with novel means for conveying the fuel from the hopper or magazine to the combustion zone.

5 A still further object is to provide a stoker having a combustion chamber adapted to operate on the cross draft principle, the tuyères of which are continuously cooled by the heating medium of the heating system itself.

10 Another object is to provide an automatic stoker with novel combined manual and automatic adjusting means whereby a predetermined relationship is constantly maintained between the amounts of air supplied and fuel fed to the combustion chamber.

15 A further object is to provide an automatic stoker with novel ash disposal means of simple structure which continuously and automatically removes the ashes from the combustion chamber of the stoker.

20 Another object is to provide novel agitating means for feelers of the hopper type which effectively prevent clogging of the feeder due to arching at the outlet thereof of the material being fed.

25 A still further object is to provide an automatic stoker embodying a combustion chamber of novel structure built up from a plurality of individual hollow-walled sections.

30 Still other objects include the provision of a novel auxiliary thermostatic control for periodically starting and stopping the stoker independently of the normal thermostatic controls and without heating the building, novel dust trap means wherein fine ash blown through the combustion chamber is collected and prevented from fouling the flues and smoke pipes, and novel means for deadening the noise produced by the blower and other high speed parts of the apparatus.

35 These and other objects will appear more fully from a consideration of the detailed description of the invention which follows. Although several embodiments of the present invention have been described and illustrated in the accompanying drawings, it is to be expressly understood that these drawings are for the purpose of illustration only and are not to be construed as a limitation of the scope of the invention, reference being had for that purpose to the appended claims.

40 In the drawings, wherein like reference characters indicate like parts throughout the several views:

45 Fig. 1 is a front elevation of one embodiment of the present invention showing an automatic stoker connected to a steam generator or water heater of the usual type (and which for convenience will hereinafter be referred to by the generic term "boiler") and provided with novel automatic thermostatic control means;

150 Fig. 22 is a sectional view taken substantially on the line 22—22 of Fig. 21.

155 Referring now to Figs. 1, 2 and 3, there is disclosed therein a heating plant or system comprising a boiler and a novel combined automatic stoker and furnace detachably connected thereto, the stoker not only including fuel supply and feeding means but also having a combustion chamber which is exterior of the boiler, thus greatly simplifying the disposal of ashes and reducing the fouling of the heating surfaces and flues of the furnace by fine ash and dust. This embodiment of the present invention also includes a novel combustion chamber operating on the cross draft principle and wherein a predetermined thickness of fuel bed is insured at all times, means for utilizing the heating medium of the system for cooling the combustion chamber and preventing fusion of the tuyères, improved fuel feeding means for feeding fuel from the hopper to the combustion chamber, novel means within the hopper for preventing arching of the fuel at the outlet thereof, improved ash disposal means, automatic regulating means for maintaining a predetermined relationship between the amounts of air supplied and fuel fed to the combustion chamber, and novel thermostatic control means for automatically governing the operation of the stoker for preventing extinguishment of the fire therein during short periods of warm weather.

160 In the form shown, the heating plant comprises a boiler 23 of any desired type and an automatic stoker and furnace, indicated generally at 24, the principal elements of which are a fuel hopper or magazine 25 from which fuel is supplied to a combustion chamber or burner 26 by a novel fuel feeding mechanism 27, combustion being supported in combustion chamber 26 by air which is supplied under pressure from a fan or blower 28 through an air trunk or wind box 29 to the burning zone 30 of combustion chamber 26, the gaseous products of combustion then passing through a

conduit 31 into the interior of furnace 23. In the form shown, furnace 23 is of the hot water or steam type having a water jacket 32 through which the heating medium circulates and in which it is heated, a supply pipe or conduit 33 leading from the top of water jacket 32 to the radiators or heating devices disposed throughout the enclosure being heated, and a return pipe or conduit 34 connected to water jacket 32 at its lower portion for returning the heating medium thereto. In the embodiment illustrated, conduit 31 of the stoker 24 is detachably connected to and delivers the gaseous products of combustion from combustion chamber 26 into the ash pit 35 of boiler 23, the hot gases then passing upward through and around the heating surfaces 36 of the boiler and exhausting through smoke pipe 37 to the chimney or flue. As is evident from Figs. 1 and 3, the arrangement of an automatic stoker and furnace detachably connected to a boiler requires very little reconstruction or rearrangement of the boiler parts, it being necessary only to provide a suitable opening 38 in the side of ash pit 35 to receive the end of conduit 31, and, if desired, to provide the side of ash pit 35 opposite to opening 38 with a baffle 39, built up of firebrick or other suitable refractory material, for preventing the hot gases from injuring ash pit housing 40, and also for deflecting the hot gases upward into the heating chamber of the furnace.

Referring now more particularly to the component elements of combined automatic stoker and furnace 24, fuel hopper 25, which is preferably made of sheet iron or other similar material, is substantially vertical in order that the fuel may feed therefrom by gravity, and is provided with at least two gradually convergent walls 41 and 42 which form a comparatively restricted outlet 43. At the lower or outlet end of hopper 25, convergent wall 42 is suitably secured in any desired manner to one end of a substantially semicircular housing or casing member 44, the other end of which is likewise secured to the inlet or bottom end of combustion chamber 26. Fuel feeding mechanism 27 is coaxial with semicircular housing member 44, and is provided with a rotatable drum 45 to the periphery of which convergent wall 41 of fuel hopper 25 is substantially tangent at its lower or outlet end. Combustion chamber 26 is so located that one of its walls is also substantially tangent to the periphery of drum 45 of the fuel feeding mechanism, thus providing an annular space 46 between the periphery of drum 45 and housing member 44 into which fuel is fed from outlet 43 of hopper 25, through which it is carried by the fuel feeding means later to be described, and from which it is delivered into the inlet 47 of combustion chamber 26. As is shown best in Fig. 3, inlet 47 of combustion chamber 26 is somewhat larger in cross section than annular space 46 in order to allow the incoming fuel to become mixed and agitated at this point.

The body of fuel thus fed to combustion chamber 26 is, due to the continuous underfeed from feeding mechanism 27, moved upward through said combustion chamber, is burned in burning zone 30, and finally approaches the outlet or exit 48 of the combustion chamber as ash or clinker, whence it is automatically and continuously removed by novel ash disposal means which, in the form shown, comprise a sheet metal trough 49 which is secured to one of the walls of combustion chamber 26 and in communication with exit 48 thereof, and into which the ashes over-

flow by gravity. As indicated in Fig. 2, trough 49 is downwardly inclined and is connected at its lower end to a chute 50 which in turn discharges through an opening in a cover 51 into a suitable removable ash can or receptacle 52.

Referring now to Figs. 12 and 13, there are shown therein in detail the novel fuel feeding means of combined automatic stoker and furnace 24 which are shown somewhat schematically in Figs. 1, 2 and 3. In the embodiment illustrated, 10 rotatable feed drum 45 is provided at each end with a disc-shaped flange 53, secured thereto in any suitable manner, between which flanges are housed the bottom or outlet end of hopper 25, semicircular housing member 44, and the forward 15 portion of the bottom or inlet end of combustion chamber 26. Flanges 53 are preferably made integral with drum 45 and are provided with outwardly extending central bosses 54 in which are housed outwardly extending stub shafts 55, the latter being journaled in suitable bearing bosses 56 mounted on brackets 57 which are in turn supported by a large base 58 on which the major portion of the stoker assembly rests. Flanges 53 are also provided with a plurality of inwardly 20 projecting bearing bosses 59 which are circumferentially spaced around the inner faces of said flanges and so positioned with respect to drum 45 that oscillating shafts 60 journaled therein will just clear the inside surface of drum 30 35 45. Rigidly secured to each of oscillating shafts 60 are a pair of lever arms 61 to the outer ends of which are pivotally secured the laterally spaced arms 62 of fuel feeding blades or paddles 63. In the embodiment shown, four such paddles 63 are 35 provided, and since they extend substantially diametrically across the interior of drum 45, arms 62 must be suitably spaced so as to allow movement of each blade independently of the other. Since, in its fuel feeding position, each blade 63 40 must extend outwardly beyond the periphery of feeding drum 45 into annular space 46 so as to engage the fuel, suitable longitudinal slots 64 are provided in the periphery of drum 45 through which blades 63 are adapted to reciprocate.

Novel means are also provided for imparting reciprocating movement to said blades as drum 45 is rotated, said means being especially adapted to make the outward extension of the blades yielding in character in order that breakage or straining of the parts may be avoided should a blade strike unusual resistance, due to foreign matter in the fuel, during its outward extension, while the retraction of the blades is performed as a positive operation. As shown, oscillating 50 shafts 60 are each extended at one end outwardly through one of flanges 53 and have secured to said outwardly extending ends suitable arms 65 on the ends of which are mounted suitable cam rollers 66. Rigidly secured to, and preferably 55 formed integral with, the bearing boss 56 on the side of the feeding mechanism from which cam rollers 66 project is an arm 67 in the outer end of which is pivoted an oscillating cam member 68 counterbalanced by a suitable counterweight 6 69 adjustably mounted on an arm 70 secured to said oscillating cam member 68.

As is shown best in Fig. 12, cam rollers 66 are adapted to engage the surface of cam member 68 in succession as drum 45 is rotated in a manner later to be described, and the contour of cam member 68 is such that the travel of each cam roller 66 therealong serves to rotate the shaft 60 to which it is connected and thereby, through lever arms 61, move its associated fuel feeding 7

blade or paddle 63 from its inner retracted position, wherein the end of said blade is within the outer periphery of drum 45, outwardly through slot 64 into contact with and through the fuel which is fed into annular space 46 from outlet 43 of hopper 25 and into engagement with the inner surface of housing member 44. After cam roller 66 clears cam surface 68, blade 63 is maintained in its outward position through its own 10 inertia until it approaches the inlet or entrance to combustion chamber 26. At this time, cam roller 66 contacts a fixed cam member 71 rigidly secured to bracket 57 of the supporting framework. Movement of cam roller 66 along cam surface 71 15 gives a positive counter-clockwise rotation to shaft 60 and withdraws blade 63 through slot 64 to its fully retracted position within drum 45 just before said blade reaches the inlet to the combustion chamber.

20 Since cam member 68 is pivotally mounted on arm 67, and although it is normally maintained in a predetermined position by counterweight 69, should the end of blade 63 strike foreign material in the fuel in annular space 46 such that usual 25 resistance is offered to its outward extension, cam member 68 will rotate about its pivot and thereby provide a yielding pressure against cam roller 66 rather than a positive force, and allow blade 63 to ride over the obstacle encountered until it reaches a point where it can find 30 its way through the less resisting body of fuel.

Suitable means are provided for driving fuel feeding mechanism 27 at any desired speed so as 35 to feed fuel to combustion chamber or furnace 26 in sufficient amounts to properly heat the enclosure in which the heating plant is installed. As illustrated somewhat schematically in Figs. 1 and 2, an electric motor 72, preferably of the constant speed type, is provided adjacent the stoker 40 assembly and drives the fuel feeding mechanism through a suitable speed reduction device. As shown, the shaft of motor 72 is connected to one element of a speed reduction gear train housed in a casing or housing 73, the output end of said 45 mechanism driving a worm gear 74 which is rigidly mounted on one end of a shaft 75, on the other end of which is secured a worm 76 which in turn engages a plurality of teeth 77 forming a gear on the periphery of one of flanges 53 of the fuel feeding mechanism, so as to drive drum 45 50 in a counter-clockwise direction, as viewed in Figs. 1, 3 and 12. It will be obvious that the speed at which fuel feeding drum 45 is rotated is very much slower than that at which motor 72 rotates, 55 and that any of the well known types of speed reduction mechanism may be installed in casing 73 in order to obtain this reduction. Such mechanism is also preferably provided with manually operable means such as a lever 78 for changing 60 the gear ratio of the speed reduction mechanism and thereby varying the speed at which the fuel feeding drum 45 is rotated. In the embodiment shown movement of lever 78 to the right, as viewed 65 in Fig. 1, reduces the speed at which drum 45 is rotated.

Referring now to the detailed structure of combustion chamber 26, it will be seen from Figs. 3-11 that this combustion chamber or burner is built up from a plurality of hollow sections, preferably of cast iron, the sections being secured together in series by a plurality of hollow nipples which are screwed into suitable threaded bosses or openings in each section. As shown in Fig. 3, 70 which is a sectional view taken intermediate the 75 ends of combustion chamber 26, each section of

said chamber intermediate the ends is composed of two pieces, a front piece indicated generally at 79 and shown in detail in Figs. 8 and 9, and a rear piece indicated generally at 80 and shown in detail in Figs. 6, 7, 10 and 11. All of the intermediate sections made up of front and rear pieces 79 and 80 are assembled together in series by suitable hollow nipples 81 which are screwed into threaded bosses or openings 82. The intermediate sections thus assembled are then closed 10 at each end by means of unitary side sections indicated generally at 83 and shown in detail in Figs. 4 and 5. As shown in Figs. 4 and 5, end sections 83 are provided with a solid outer wall 84 and an inner wall 85 from which project 15 threaded bosses 82, the space between outer and inner walls 84 and 85 thus providing free communication between all of the openings in bosses 82 for the circulation of the heating medium in a manner later to be described. 20

End sections 83 are also provided with inwardly projecting ribs 86 which are adapted to abut similar ribs formed on the adjacent intermediate sections of the combustion chamber and to space said sections the proper distance apart so as to 25 permit the flow of air and hot gases of combustion therethrough. For this latter purpose, the front portion of each end section 83 corresponding to front pieces 82 of the intermediate sections is provided with a plurality of V-shaped 30 projections or lugs 87 of the same height as ribs 86, separated at their bases by suitable spaces 88 which are adapted to act as tuyères through which the air supplied to the combustion chamber flows. Similarly, the portion of each end section 83 corresponding to the front legs of rear pieces 80 of the intermediate sections is provided with V-shaped lugs 89 similar to lugs 88 but with their vertices directed in the opposite direction, between which lugs there are provided suitable 40 spaces 90 which act as tuyères through which the hot gases of combustion are exhausted from the combustion chamber. 35

As shown in Figs. 6 and 7, rear pieces 80 of the intermediate sections each comprises a front leg 45 91 and a rear leg 92, both being substantially L-shaped and joined at their upper ends, front leg 91 acting as the rear wall of the combustion chamber and the space 91 between legs 91 and 92 forming the exhaust conduit through which the 50 hot gases of combustion pass from the combustion chamber to the boiler 23. Front pieces 79 of the intermediate sections each comprises a single, substantially vertical leg 93 which acts as the front wall of the combustion chamber 26. Both 55 front and rear pieces 79 and 80 of the intermediate sections are provided with threaded bosses 82, ribs 86, V-shaped lugs 87 and 89 and openings 88 and 90 similar to those already described in connection with Figs. 4 and 5. As shown in Figs. 60 10 and 11, each leg 91 is substantially triangular in cross section and provided with a hollow space 94 therein with which the openings in bosses 82 communicate and through which the heating medium is adapted to circulate. It will be understood 65 that legs 92 and 93 of rear and front pieces 80 and 79 are similar in structure to leg 91.

As previously indicated, suitable means are provided for circulating the heating medium of boiler 23 inside of the various sections making up 70 combustion chamber 26 in order not only to cool the elements of this chamber, particularly the tuyères formed by lugs 87 and 89 and openings 88 and 90, but also to increase the efficiency of the heating plant by thus adding to the heat content 75

of the heating medium. As shown, one of the intermediate sections of the combustion chamber is provided with a suitable inlet opening 95 and outlet opening 96 to which are connected suitable inlet and outlet pipes 97 and 98 leading from and to water jacket 32, respectively. Inlet and outlet openings 95 and 96 communicate with the hollow space 94 within legs 91 and 92 of the particular intermediate section concerned, and the heating medium which is thus supplied through pipe 97 and inlet opening 95 circulates inside of all of the intermediate and end sections comprising the combustion chamber through hollow nipples 81 and the circulating space in the end sections 83 between walls 84 and 85. The temperature of the parts of the combustion chamber is thereby prevented from running materially above that of the heating medium in boiler 23.

Referring again to Figs. 1, 2 and 3, it will be seen that the space included between legs 93 and 94 of the front and rear pieces of the intermediate sections provides a combustion chamber of definite size, two of the opposite walls of which are gradually divergent from the entrance to the exit thereof. Moreover, since the feeding of fuel to combustion chamber 26 by fuel feeding mechanism 27 not only maintains said chamber full of fuel at all times but also moves said body of fuel through said chamber due to its underfeed characteristics, it is evident that the fuel bed thus supplied is of a uniformly increasing, predetermined thickness.

In order that most efficient combustion shall take place within combustion chamber 26, suitable means are provided for supplying air under pressure thereto in a manner so as to create a cross draft substantially transverse to the direction of movement of the fuel bed therethrough. As shown, and as previously described, V-shaped lugs 87 and openings 88 in front pieces 79 of the sections making up the combustion chamber form tuyères through which air is adapted to be supplied to the burning zone 30 of the combustion chamber 26. For this purpose, combustion chamber 26 is provided with a wind box or air trunk 29 communicating with the inlet tuyères 87, 88, which trunk is supplied with air under pressure from a suitable blower or fan 28 through a conduit 99. Blower 28 is directly connected to and driven by motor 72. Wind box 29 may, if desired, be provided with a suitable cover 100 which may be removed whenever desired for inspection of the air trunk and removal of any fine ash or dust which might collect therein.

The hot gases which are produced by combustion within burning zone 30 are exhausted from the combustion chamber through the tuyères 89, 90 formed in the front legs 91 of rear pieces 80 of the sections comprising said combustion chamber, and are conducted through conduit 31 into ash pit 35 of boiler 23 whence they flow upward in contact with the heating surfaces 36 of said boiler and heat the heating medium in the usual manner. It will be seen that the L-shapes of legs 91 and 92 are such as to impart a substantial curvilinear velocity to the hot gases in conduit 31 thus increasing the tendency for any fine ash or dust particles which might be entrained in the hot gases to be deposited in ash pit 35 of boiler 23 and on the bottom of conduit 31 formed by the horizontal portion of L-shaped legs 91 whence said particles can be readily removed through ash pit door 100' of boiler 23 and an auxiliary door 101 in one of side sections 83 of the combustion chamber 26.

In connection with this detailed description of the combustion chamber 26, it will be noted that a larger number of outlet tuyères 89, 90 have been provided than of inlet tuyères 87, 88, this construction being preferable because of the increase in the volume of the gases as they pass through burning zone 30 due partly to chemical combination and partly to expansion by heat. It has also been mentioned that the combustion chamber is enlarged in cross section as it extends upwardly, this construction being preferable in order that the increased thickness of the fuel bed in the upper portion of the combustion chamber will offer greater resistance to the passage of air therethrough and thus force a greater portion of air to pass through the lower portion of the burning zone where the greatest amount of air is required to sustain combustion.

In stokers of the type described, difficulty is often encountered in properly feeding fuel from the hopper because of a persistent tendency of the fuel to bridge or arch at the discharge outlet thereof, no further fuel feeding down out of the hopper when this arching occurs until the arch is broken up. Novel means are therefore provided for agitating the fuel within hopper 25 and thereby continually breaking up any arch which might be formed adjacent the outlet 43 of said hopper. As shown in Figs. 1, 2, 3, 14 and 15, hopper 25 is provided with a pair of substantially rectangular, smooth surfaced agitator plates 102 slidably mounted inside of said hopper adjacent the convergent walls 41 and 42. Plates 102 are of substantially the same size as walls 41 and 42 of the hopper and their lower edges lie adjacent outlet 43, said lower edges being preferably chamfered or sharpened as indicated at 103. Plates 102 are pivotally fastened at their upper edges to links 104 which are in turn pivotally secured to a walking beam 105 at points 40 on opposite sides of the pivot 106 thereof. Walking beam 105 is pivotally mounted on a suitable cross member 107 which is secured as by brackets 108 to the open top of hopper 25. One end of walking beam 105 extends forwardly over the 45 edge of hopper 25 and is pivotally connected to the upper end of a connecting rod 109 the lower end of which is pivotally secured to a crank pin 110 carried by a crank arm 111 secured to an oscillatable shaft 112 journalled in suitable bearings 113 secured to the front wall 42 of hopper 25. Shaft 112 is also provided with a second crank arm 114 having a crank pin 115 on which is pivoted the upper end of a connecting rod 116, the lower end of which is pivotally mounted on 55 a crank pin 117 carried by a disc 118, the latter being rigidly attached to the end of a shaft 119 forming part of the speed reduction mechanism housed in casing 73. The throw of crank pin 117 carried by disc 118 is preferably less than half 60 that of crank pin 115, so that as shaft 119 is slowly revolved from motor 72 through the speed reduction mechanism, crank pin 114 and its associated shaft 112 are given only an oscillatory movement, which movement is in turn transmitted to walking beam 105 thereby imparting to agitator plates 102 an alternate reciprocating movement substantially parallel to the walls of hopper 25 and the fuel contained therein. This alternate reciprocating motion of plates 102 gives 70 to the fuel within the hopper adjacent outlet 43, where the arch attempts to form, a torsional or twisting movement which alternately raises and lowers the imposts of the arch and thereby completely breaks it up or prevents its formation. 75

Although, for all ordinary purposes, successful operation may be obtained with plates 102 which are smooth on both sides, it is within the contemplation of this invention that, where conditions require it, plates 102 may be provided with small projections or otherwise suitably roughened on the sides which contact with the fuel in order to increase the frictional engagement therewith. Also, in some instances where conditions warrant it, one of the two plates shown may be omitted, although best results are obtained by using both, as in the preferred embodiment.

In connection with the fuel agitating means just described, it has been discovered that the same device is equally efficient for the prevention of arching and clogging of a number of other materials which are normally fed from hoppers by gravity in a manner somewhat similar to that in which the fuel is fed from hopper 25 in the automatic stoker herein disclosed. It is therefore within the contemplation of this invention that the invention embodied in agitator plates 102 and their associated mechanism may likewise be utilized in connection with gravity feeders in general, as for feeding grain, chemicals and the like.

Where automatic stokers of the type herein disclosed are installed in heating systems for residences, apartment houses and the like, it has hitherto been the custom to install a temperature or pressure responsive device on the furnace or boiler to operate in conjunction with a thermostat located within the house for controlling the temperature to which the house is heated. Such an installation is diagrammatically illustrated in Fig. 1 wherein a temperature or pressure responsive control device 120 is mounted on top of boiler 23 and subject to the temperature-pressure condition of the heating medium within water jacket 32, said device being adjustable for different temperatures or pressures within the range of operation of the heating system so that when the water or steam attains the maximum temperature or pressure, the current through an electric circuit 121 in which control device 120 is connected will be broken thereby operating a relay switch 122 which controls the supply of current in circuit 123 leading to the electric motor 72 of the automatic stoker, thereby stopping motor 72 and interrupting the operation of the stoker. As soon as the temperature or pressure of the heating medium drops slightly, the regulator or control device 120 again closes circuit 121, actuates relay switch 122 and again starts motor 72 and stoker 24. Operating in conjunction with regulator 120 is a thermostat 124 located in the enclosure being heated and set for the desired temperature to be maintained therein. When this temperature is reached, thermostat 124 operates to break an electric circuit 125 in which it is connected and, since circuit 125 also controls relay switch 122, stops motor 72 and the stoker. When the temperature at thermostat 124 drops slightly, circuit 125 is again closed and the stoker again started.

With this installation, the main supply circuit 123 to motor 72 of the stoker is controlled by both regulator 120 and thermostat 124 in such a manner that when either or both of said devices have operated to open their respective circuits, motor 72 is stopped and the stoker is not operating so as to feed fuel and air to the combustion chamber. By this means, the heating medium within boiler 23 is prevented from reaching an excessive temperature or pressure at times,

such as during very cold weather, when long continued operation of the stoker would raise the temperature or pressure of the heating medium to a dangerous degree before the temperature within the house or enclosure being heated reached the required degree for which the thermostat 124 is set.

In the early fall and late spring, however, there are often periods of time lasting from twenty-four to forty-eight hours when the outdoor temperature is above that required to be maintained within the enclosure being heated, with the result that thermostat 124 keeps the stoker shut down during this entire period of time and the fire in the combustion chamber becomes extinguished because of lack of additional fuel and air over this long period of time. This spell of warm weather then terminates in a cool wave with the result that thermostat 124 starts the stoker but, since there is nothing to cause ignition of the fuel in the combustion chamber, fuel is consequently fed into the burner, is unburned and no heat is generated. In order to cure this defect, novel means are provided by the present invention for controlling the operation of the stoker independently of regulator 120 and thermostat 124, and thereby preventing extinguishment of the fire in combustion chamber 26 during short periods of warm weather.

As shown, a third regulator 126 of any desired construction is installed in return line 34 of the heating system, with a temperature sensitive bulb 127 directly exposed to the heating medium in return line 34. An electric circuit 128 leads from regulator 126 to relay switch 122 and is so connected as to operate said switch independently of circuits 121 and 125. Regulator 126 is calibrated to operate at a temperature materially below that at which regulator 120 is set, and its electrical connections to relay switch 122 are such that it will start motor 72 and stoker 24 when the temperature of the heating medium reaches this low point even though regulator 120 and thermostat 124 have operated to break their respective circuits 121 and 125.

By way of example, it may be stated that, on a steam boiler, regulator 126 may be set to operate at a temperature slightly below that of steam, as at 180° F. With regulator 126 set at this low temperature, a period of warm weather would cause thermostat 124 to stop the stoker, but when the water in boiler 23 has cooled down to 180° F., regulator 126 would operate to complete the circuit to motor 72 and to start the stoker, and would cause it to operate for a short period of time until the temperature of the water in the boiler rises slightly above 180° F., whereupon regulator 126 would operate to stop the stoker until the temperature of the heating medium again fell below 180° F. This causes an intermittent operation of the stoker for short periods of time and prevents total extinguishment of the fire in the combustion chamber, yet no heat is supplied to the enclosure being heated since the water in the boiler is maintained below the boiling point and no steam is generated. In a hot water heating system, regulator 126 may be set to operate at a temperature only slightly above any anticipated outdoor temperature, for example 85° F. This low setting is likewise maintained in hot air systems. By this means the fire in the combustion chamber of the stoker is kept alive for a substantial period of time even though the outdoor temperature is sufficiently high to

not require any heating of the enclosure, and is always in readiness for regular operation whenever the weather turns cool.

Although various means have hitherto been provided for regulating the rate at which fuel is fed into the burner of an automatic stoker, and although it is also common practice to provide some manual control means for regulating the amount of air admitted to the burner, in those stokers hitherto known the control of the fuel feed is separate and distinct from the control of the air supply, and it has been left to the operator to adjust these as best he can. This often results in an improper balance between the air admitted and the fuel fed to the combustion chamber with a consequent inefficiency in the operation of the stoker. Novel means are therefore provided in the present invention for overcoming this objection by combining with the fuel feed and air supply adjusting means, an automatic connection whereby when the relative amounts of air and fuel fed have been once adjusted, any change in the adjustment of one will automatically change the other by the proper amount.

As shown in Figs. 1 and 16, fan or blower 28 is provided with a casing 129 which is reduced in diameter at one end and provided with an axial opening therein to serve as the air inlet or supply 130 to said blower. Fitting over and around the reduced end of casing 129 forming air inlet 130 is a cup-shaped cap member 131 having a rearwardly extending stem 132 which is slidably mounted in a boss 133 formed integrally with a pair of supporting arms 134 which are suitably secured to the larger portion of casing 129 of blower 28. Cap member 131 is also provided with a lug 135 to which is pivotally connected one end of a suitable connecting rod 136 the opposite end of which is pivotally secured to the lower end of regulating lever 78 of the speed reduction mechanism housed within casing 78.

As previously mentioned, movement of lever 78 to the right, as viewed in Fig. 1, decreases the speed of operation of the fuel feeding mechanism 27, and, due to the operative connection between the lower end of said lever and cup member 131, it is evident that such movement will also move said cup member to the left, as viewed in Fig. 1, and decrease the effective size of the air inlet 130 to blower 28, and hence decrease the amount of air supplied thereby to combustion chamber 26. Suitable manual adjusting means, such as a turn buckle 137, is also provided in connecting rod 136 for manually adjusting the position of cap member 131 at any given position of speed regulating lever 78. Once this adjustment is properly made for any particular stoker installation, any further change in adjustment of the speed of operation of the fuel feeding mechanism will automatically operate to vary the amount of air supplied to blower 28. For example, moving lever 78 to the right, as viewed in Fig. 1, reduces the rate at which fuel is fed into combustion chamber 26, and also draws cup member 131 closer over air inlet 130 of blower 28 and correspondingly reduces the amount of air which can be taken in thereby. Similarly, a movement of lever 78 to the left increases the rate of fuel feed and automatically pushes cup member 131 to the right thereby increasing the amount of air supplied to the blower. By this means the proper ratio between air supplied and fuel fed to combustion chamber 26 is automatically maintained under

all conditions, and a high efficiency of combustion is obtained.

Suitable means are also provided by the present invention for reducing or eliminating the noise which is normally produced by the high speed moving parts and the passage of the air through the blower of automatic stoker installations of the type herein disclosed. As shown in Figs. 1, 2, 16 and 17, the noise due to the moving parts of electric motor 72, blower 28 and the speed reducing mechanism housed in casing 73 is deadened by mounting these devices upon an individual base 138 which is entirely separate and distinct from the main stoker base 58, and by supporting said base 138 upon a plurality of coil springs 139 or other suitable resilient supports, said springs resting upon a suitable asbestos base 140 on the furnace room floor. In order to permit free vibration of base 138 without interfering with the stoker drive, shaft 75 which transmits the driving energy from the speed reduction mechanism 27 may be provided with a pair of suitable flexible couplings 141 of any desired construction.

The noise of the moving parts of blower 28 is further deadened by constructing blower casing 129 with double walls and an air space therebetween. As shown best in Figs. 16 and 17, casing 129 comprises an outer wall 142 which is preferably made of hard fiber or other non-resonant material, an inner wall 143 secured in any desired manner to outer wall 142 and preferably made of metal, and a dead air space 144 between said walls. Cap member 131 may also be provided with a double wall similar to that described for casing 129.

In order to deaden the noise caused by the flow of air through blower 28, the overlapping arrangement of cap member 131 and the reduced portion of casing 129 is provided in order to make the inlet passageway to the blower a tortuous path as indicated by the arrows in Fig. 16. By this arrangement, the whistle which is ordinarily produced by the inrushing air to a blower is practically eliminated. A further improvement which decreases the noise produced by the blower lies in the provision of a short bellows-shaped section 145 of flexible, non-resonant material, such as rubber, leather or other similar fabric, interposed in conduit 99 which conducts the air supplied by blower 28 to wind box or air trunk 29.

With this arrangement, the hum of motor 72 and the movement of the gears in housing 73 is silenced by the flexibility of springs 139, while the roar of fan or blower 28 is deadened by the sound deadening walls of casing 129, and by the tortuous inlet passageway which the air must travel in reaching the blower. Flexible bellows section 145 also permits a free vibration of the high speed moving parts without conducting any sound to the stationary parts of the stoker.

Although it will be evident from the preceding description how the various elements of the present invention function, the operation of the embodiment shown in Figs. 1-17 may be summarized as follows: Assuming that fuel hopper 25 is filled with fuel, and that the temperature or pressure conditions of the enclosure being heated and the heating medium are such that relay switch 122 is in position to close the main supply circuit 123 to electric motor 72, said motor will be driving fuel feeding mechanism 27 through the speed reduction mechanism, and will be directly driving blower 28 for supplying air to the combustion chamber 26. Fuel is fed from hopper 25 by

gravity through outlet 43 and into annular space 46 between housing 44 and drum 45. Should there be any tendency for the fuel to arch or clog adjacent outlet 43, agitator plates 102 which are being alternately reciprocated through the driving connections from shaft 119 of the speed reduction mechanism will act to break up any such arch or to prevent its formation. The fuel which is fed into annular space 46 is engaged by paddles 63 as feeding drum 45 is rotated in a counter-clockwise direction, said paddles or blades being alternately extended and retracted beyond and within the periphery of drum 45 by the action of cam members 68 and 71. Should any blade 63 encounter unusual resistance to its outward extension due to foreign matter in the fuel, cam member 68 will oscillate about its pivot to allow blade 63 to ride over the obstacle until it reaches a point where it can find its way through the less resisting body of fuel and assume its fully extended position in contact with the interior surface of housing 44. The fuel is thus carried around through annular space 46 by blade 63 and is discharged upwardly into inlet 47 of combustion chamber 26, the enlargement of said inlet over the size of annular space 46 permitting the incoming fuel to become mixed and agitated at this point.

The fuel is then fed upwardly within combustion chamber 26 due to the continuous feed of additional fuel below it, and gradually progresses through burning zone 30 of the combustion chamber where it unites with the draft of air which is being blown, transverse to the direction of movement of the fuel body, through inlet tuyères 87, 88 from air trunk 29 to which it is supplied by blowers 28. The hot gaseous products of combustion are exhausted through outlet tuyères 89, 90 into conduit 31 whence they pass into ash pit 35 of boiler 23 and circulate upwardly therefrom in contact with the heating surfaces 36 of said boiler, finally escaping through smoke pipe 37 to the flue or chimney. After passing through burning zone 30 and being completely consumed, the fuel reaches the upper portion or exit 48 of combustion chamber 26 as ash or clinker and gradually overflows by gravity into ash discharge trough 49 whence it passes through chute 50 into ash can 52. In the meantime, the tuyères and other parts of combustion chamber 26 have been cooled and maintained at a temperature not materially higher than that of the heating medium within boiler 23 due to the circulation of said heating medium through the hollow walls of the sectional elements making up said combustion chamber.

The operative connection between regulating lever 18 of the speed reduction mechanism and cap member 131 covering the air inlet to blower 28 insures that at all times the proper ratio of fuel fed and air supplied to the combustion chamber is automatically maintained. Likewise, the resilient, independent mounting of motor 72, blower 28 and the speed reduction mechanism greatly decreases the noise caused by the high speed moving parts of said devices, as does the double walled casing of the blower, the tortuous-shaped inlet passageway thereto and the flexible bellows-shaped section 145 interposed in conduit 89.

Should the enclosure being heated reach the desired degree of temperature, or should the temperature or pressure of the heating medium rise to a predetermined maximum point, thermostat 124 or regulator 120 will act to open the supply

circuit 123 to motor 72 and stop the stoker until such time as the temperature within the enclosure or in the heating medium falls below that at which said regulating devices are calibrated. Should a period of warm weather occur during the time when the automatic stoker is in operation, such that it is not required that the furnace heat the enclosure, auxiliary regulator 126 will function to intermittently start and stop the stoker so as to prevent complete extinguishment of the fire within the combustion chamber 26.

In the usual types of stoker installations where the combustion chamber is located within the fire box of the furnace, it is a common defect that the blast of air from the fan or blower carries foreign particles of ash and dust up into the flues and smoke pipes of the furnace, covering them with a coating which reduces the heating efficiency of the installation, and in some cases blows this dirt through the chimney and discharges it on the house tops and surrounding lawns. The embodiment of the present invention illustrated in Figs. 1-17 obviates this defect to some extent by virtue of the fact that the combustion chamber is located outside of the boiler and the shape of the conduit through which the hot gases pass on their way to the boiler is such as to cause most of the fine ash and dust to be deposited in the ash pit of the boiler.

Referring now to Fig. 18, there is disclosed therein still another means for reducing or eliminating this defect. The stoker installation disclosed in Fig. 18 is substantially the same as that previously described, although several features have been omitted from the illustration in the interest of simplicity, with the exception that legs 91 and 92 of the rear pieces of the intermediate sections making up combustion chamber 26 are not only provided with spacing ribs 86 around the outside edges thereof, but also have additional ribs 146 of the same height as ribs 86 around the inner edges thereof so as to form a restricted passageway or conduit 147 for the gaseous products of combustion. The bottom horizontal portion of each leg 91 is also provided with a pair of upwardly extending horizontally spaced partitions 148 and 149, the space between partitions 148 and the vertical parts of legs 91 forming a main ash or dust trap 150, while the space between partitions 148 and 149 forms a secondary trap 151. Because of the fact that passageway 147 is restricted in cross sectional area by ribs 146, the hot gases of combustion exhausting through tuyères 89, 90 attain a relatively high velocity in passing downwardly through this passageway, and since the fine particles of ash and dust entrained in said gases are heavier than the gases, they have a tendency to continue a vertically downward course and to be deposited in main trap 150. Any residual particles which may be carried beyond trap 150 will be deposited in secondary trap 151. As the hot gases turn the curve in passageway 147 formed by the L portion of leg 92 at high velocity, centrifugal force aids in separating the heavier ash and dust particles from the hot gases and in depositing them in traps 150 and 151. The ash and dust collected in traps 150 and 151 may be periodically removed through a suitable door in the side of combustion chamber 26 similar to that indicated at 101 in Fig. 1. The almost negligible quantity of dust which escapes traps 150 and 151 is deposited in ash pit 35 of boiler 23 whence it may be removed through the ash pit door as desired.

Although in the preferred form of the invention, the fuel is fed into a substantially vertical combustion chamber, it will be understood that, if desired, the combustion chamber may be inclined at any desired angle from the vertical without departing from the invention, as in the case of very small residential installations where it is preferable that the combustion chamber lie horizontally. Figs. 18-22 disclose such an installation wherein the combustion chamber is substantially horizontal and the air supplied thereto provides a substantially vertical, downward cross draft. The elemental structure and principles of operation of this latter embodiment of the invention are fundamentally the same as in the embodiment of Figs. 1-17, although various minor improvements such as the hopper agitating means, noise deadening means and the automatic fuel feed and air supply regulating means have been omitted from the drawings in the interest of simplicity, and may be omitted in the actual installation, if desired.

As shown, fuel is fed from a hopper 25 by fuel feeding means 27 as previously described, to a substantially horizontal combustion chamber 152. The driving means for fuel feeding mechanism 27 is slightly different from that previously disclosed in that the speed reducing mechanism housed within casing 73, which is driven by motor 72, is provided with a forwardly extending shaft 153 on which is secured a drive pulley 154 which is connected by a suitable belt 155 with a similar pulley 156 secured to the driving shaft 157 of a worm 158, the latter engaging and driving a worm wheel 159 which is secured to one of stub shafts 55 of the fuel feeding mechanism. Worm 158 and shaft 157 are suitably journaled in bearing brackets 160 secured to one of a pair of legs 161 which support hopper 25 and fuel feeding mechanism 27.

Combustion chamber 152 is of substantially the same built-up construction as chamber 26 previously described, having a pair of opposite, gradually divergent walls 162 and 163 which form a combustion chamber of gradually increasing cross sectional area from its entrance to its exit, the upper wall 162 being provided with a plurality of inlet tuyères 164 and the lower wall 163 having a larger number of similar outlet tuyères 165, the construction of said tuyères being similar to those of the preceding embodiments. Air is supplied under pressure to inlet tuyères 164 from a blower 28 through conduit 99 and an air trunk or wind box 29, is forced downwardly through the moving body of fuel in burning zone 30 in a substantially vertical direction, and the products of combustion are exhausted through tuyères 165 into a chamber or conduit 166 formed below tuyères 165 by an offset portion 167 of bottom wall 163 of the combustion chamber. From chamber 166, the gaseous products of combustion are conducted at right angles through a conduit 168 into the ash pit 35 of the boiler.

As will be seen from Fig. 22, the bottom of chamber 166 is lower than that of conduit 168 thereby providing an ash or dust trap 169 in which fine particles of ash or dust are deposited from the hot gases on their way to the boiler, said ash and dust being removed when desired through a suitable door 170 in the side of chamber 166. Conduit 168 is also provided at its discharge end in ash pit 35 with a downwardly curved baffle plate 171 which deflects the hot gases downward as they enter the ash pit, the curvilinear velocity thus imparted to said gases

creating a centrifugal force which further tends to separate the fine particles of ash and dust from the hot gases and to deposit said particles in the bottom of ash pit 35.

The walls of combustion chamber 152 are made hollow in a manner similar to that previously described in order that they may be cooled by the circulation therein of the heating medium from the boiler supplied thereto through a suitable pipe or conduit 97 and returned therefrom to the boiler through a similar pipe 98.

Secured to the outlet end 48 of combustion chamber 152 is a substantially J-shaped ash pit casing or housing 172, preferably made of sheet metal, provided at its bottom portion with a suitable drawer 173 into which the ashes overflow by gravity from the outlet end of combustion chamber 152. As shown in Fig. 19, drawer 173 is provided with an outer lid 174 which closes tight around the opening in ash pit housing 172 to prevent escape of air therethrough. Ash drawer lid 174 is also provided with a suitable handle 175 for withdrawing it from housing 172 for the purposes of emptying the ashes. Ash pit housing 172 is also provided with a weighted check damper 176 pivoted thereto at its upper end as at 177, said damper tending to retard the flow of ashes so that the fuel bed will be maintained compact and the formation of cavities in the hot burning zone 30 will be prevented.

Suitable means have also been provided for preventing the escape of smoke and other gaseous products of combustion back through the fuel supply and out of hopper 25 and through the ash pit and out of housing 172. As shown, a pipe or conduit 178 is connected between wind box 29 and the inlet 47 to the combustion chamber, and an additional pipe 179 between wind box 29 and a point within ash pit housing 172 adjacent the exit 48 of combustion chamber 152. By thus leading air from wind box 29 to points adjacent the entrance and exit of the combustion chamber, the air pressure at these points is equalized with that in burning zone 30 and any tendency for smoke or other gaseous products of combustion to escape in these directions is effectively prevented.

It will be understood that in any installation where the combustion chamber is inclined at an angle to the vertical, as in the embodiment just described, fixed cam 71 of the fuel feeding mechanism is suitably located so that blades 63 are retracted within fuel feeding drum 45 at the proper time, just as they approach the discharge end of annular space 46.

Although the automatic stokers embodying the present invention have been illustrated as connected to a steam or hot water boiler, it will be understood that the invention is equally applicable to any other type of heating plant. For instance, in the case of a hot air furnace, the connections are substantially the same as those illustrated with the exception that pipes 91 and 98 leading from water jacket 32 of the boiler to the hollow walls of the combustion chamber would be replaced by air pipes, and a rapid circulation of air would be maintained through the air chamber of the furnace and the hollow walls of the stoker combustion chamber by means of a power driven fan of the type now generally used with hot air furnaces for circulating the heated air to the registers of the enclosure being heated.

There is thus provided by the present invention a new and improved form of heating plant

embodying an automatic stoker having a combustion chamber located exteriorly of the boiler and operating on the cross draft principle, thereby providing an installation which is not only efficient and dependable in operation, but also successfully solves the various problems incident to installations of this character and obviates the defects common thereto. Not only has the disposal of ashes and clinker been greatly facilitated by locating the combustion chamber outside of the boiler, but novel means have also been provided for automatically discharging said ashes and clinker from the combustion chamber, and for entrapping the fine particles of ash and dust which become entrained in the gaseous products of combustion and would otherwise be carried into the boiler and deposited on the heating surfaces and in the flues and smoke pipes thereof. The present invention also provides novel fuel feeding mechanism which permits a yielding of the moving parts should foreign obstructions be encountered in the fuel being fed, and thereby avoids breakage or straining of the mechanism, and includes novel agitating means for preventing the formation of arches in the fuel of the hopper at the comparatively restricted outlet thereof. As has previously been mentioned, this latter improvement is equally well applicable to any other form of gravity feeding hopper means where the material is subject to this same arching or clogging tendency.

Due to the novel construction of the combustion chamber provided by the present invention, a fuel bed of predetermined thickness is constantly maintained, and at the same time it is impossible for the fuel to burn through in an irregular manner and form arches because the fuel is positively fed into the combustion chamber, that is, the fuel is forced into said chamber and continually agitated by the upward or lateral thrust of the fresh fuel being fed in at the inlet end of said chamber. The walls and tuyères of the combustion chamber are continuously cooled by the circulation within the hollow walls thereof of the heating medium of the boiler itself, thereby not only preventing damage to these parts of the stoker which are exposed to high temperatures, but also increasing the heating efficiency of the heating plant as a whole. Novel means have also been provided whereby a predetermined relationship is automatically maintained between the amounts of air supplied and fuel fed to the combustion chamber, said means including a manual adjustment for the air supply independent of the fuel feed.

A further improvement provided by the present invention consists in the provision of novel auxiliary thermostatic control means for periodically starting and stopping the stoker independently of the normal controls, and without heating the enclosure, in order that the extinguishment of the fire in the combustion chamber may be prevented during short periods of warm weather which may occur during the time when the stoker is in operation. Also, novel means are included for deadening the noise produced by the blower and other high speed parts of the stoker apparatus and for preventing transmission of these noises to other parts of the heating plant. The stoker installation thus provided is adapted for use with any of the usual types of heating plant, large or small, and is readily and inexpensively installed with a minimum of reconstruction and rearrangement work.

75 It will be obvious that the invention is not lim-

ited to the forms described and illustrated in the accompanying drawings, but is capable of a variety of mechanical embodiments. For example, any desired form of fuel hopper may be substituted for the specific form shown and described, and any suitable forms of speed reduction mechanism may obviously be employed for driving the fuel feeding mechanism. Likewise, it will be understood that any known means of automatic control of the heating plant may be substituted for the system described and illustrated. Moreover, features illustrated only in conjunction with one embodiment may be used in other embodiments, and various combinations can be made of the several features illustrated and described, within the present invention. Various other changes, which will now appear to those skilled in the art, may be made in the form, details of construction and arrangement of the parts without departing from the spirit of the invention, and reference is therefore to be had to the appended claims for a definition of the limits of the invention.

What is claimed is:

1. A combined automatic stoker and furnace unit comprising a fuel hopper, a combustion chamber extending upwardly at an acute angle thereto, means intermediate said hopper and said combustion chamber for feeding fuel from said hopper to said combustion chamber and for moving the body of fuel upwardly through said combustion chamber, means for providing a cross draft of air from one side of said combustion chamber to the other substantially transverse to the direction of movement of the fuel body therethrough for supporting combustion therein, and means for conducting the gaseous products of combustion therefrom.

2. In an automatic stoker, a fuel hopper, an elongated, stationary combustion chamber, means between said hopper and said combustion chamber for feeding fuel from said hopper to said combustion chamber and for moving the body of fuel thus supplied longitudinally through said chamber, tuyères disposed in opposite walls of said combustion chamber, means for supplying air to the moving body of fuel through the tuyères in one wall of said chamber, and means for exhausting from said chamber the gaseous products of combustion through the tuyères in the opposite wall, whereby the draft in said chamber is substantially transverse to the direction of movement of said body of fuel.

3. In a heating plant, a fuel supply, a combustion chamber having gradually divergent walls from the entrance to the exit thereof, the walls of said chamber providing a burning zone of definite cross sectional area and volume, means for positively feeding fuel from said supply to said combustion chamber and for maintaining said chamber full of fuel whereby a fuel bed of predetermined thickness is provided, and tuyère means disposed in the opposite divergent walls of said chamber for providing a draft which throughout the combustion zone is across the direction of movement of fuel through said chamber.

4. In a heating plant, a fuel supply, a combustion chamber having gradually divergent walls from the entrance to the exit thereof, means for positively feeding fuel from said supply to said combustion chamber and for maintaining said chamber full of fuel whereby a fuel bed of predetermined thickness is provided, tuyères disposed in the opposite divergent walls

of said chamber, means for supplying air to the fuel bed through the tuyères in one of said divergent walls, and means for exhausting from said chamber the gaseous products of combustion through the tuyères in the opposite divergent wall, the cross sectional area of said exhaust tuyères exceeding that of said supply tuyères.

5. In a heating plant, a fuel supply, a combustion chamber having gradually divergent walls from the entrance to the exit thereof, means for positively feeding fuel from said supply to said combustion chamber and for maintaining said chamber full of fuel whereby a fuel bed of predetermined thickness is provided, tuyères disposed in the opposite divergent walls of said chamber, means for supplying air to the fuel bed through the tuyères in one of said divergent walls, means for exhausting from said chamber the gaseous products of combustion through the tuyères in the opposite divergent wall, the cross sectional area of said exhaust tuyères exceeding that of said supply tuyères, and ash removal means disposed adjacent the exit end of said chamber into which the ashes overflow by gravity.

6. In a heating plant, a fuel hopper, a combustion chamber having approximately vertical walls, means for feeding fuel from said hopper to said chamber and for moving the body of fuel thus supplied vertically upward through said chamber, tuyère means disposed in opposite walls of said chamber, means for supplying air to the fuel body through the tuyères in one of said walls, and means for exhausting from said chamber the gaseous products of combustion through the tuyères in the opposite wall.

7. In a heating plant, a fuel hopper, a combustion chamber having approximately vertical walls, said walls being gradually divergent from the bottom to the top of said chamber, means for feeding fuel from said hopper to said chamber and for moving the body of fuel thus supplied vertically upward through said chamber, tuyère means disposed in the opposite divergent walls of said chamber, and means for creating a cross draft through said moving fuel body from one of said tuyère means to the other.

8. In a heating plant, a fuel hopper, a combustion chamber having approximately vertical walls, means for feeding fuel from said hopper to said chamber and for moving the body of fuel thus supplied vertically upward through said chamber, tuyère means disposed in opposite walls of said chamber for providing a cross draft transversely from one side of said moving fuel body to the other, and ash removal means disposed adjacent the upper end of said chamber into which the ashes overflow by gravity.

60 9. In a heating plant, a fuel hopper, a combustion chamber having approximately vertical walls, means for feeding fuel from said hopper to said chamber and for moving the body of fuel thus supplied vertically upward through said chamber, tuyère means disposed in opposite walls of said chamber for creating a cross draft through said moving fuel body, and means for removing the ashes from said chamber comprising a downwardly inclined trough adjacent to and in communication with the upper end of said chamber into which the ashes overflow, and a chute connecting with the lower end of said trough and discharging into a removable ash receptacle.

75 10. In a heating plant, a fuel hopper, an elongated, stationary combustion chamber having approximately horizontal walls, means for feeding fuel from said hopper to said chamber and for moving the body of fuel thus supplied horizontally and axially through said chamber, and tuyère means disposed in a pair of opposite walls of said chamber for creating a cross draft through said moving fuel body.

5 11. In a heating plant, a fuel hopper, an elongated, stationary combustion chamber having approximately horizontal walls, said walls being gradually divergent from the entrance to the exit of said chamber, means for feeding fuel from said hopper to said chamber and for moving the body of fuel thus supplied horizontally and axially through said chamber, and tuyère means disposed in a pair of opposite divergent walls of said chamber for creating a cross draft through said moving fuel body.

10 12. In a heating plant, a fuel hopper, an elongated, stationary combustion chamber having approximately horizontal walls, said walls being gradually divergent from the entrance to the exit of said chamber, means for feeding fuel from said hopper to said chamber and for moving the body of fuel thus supplied horizontally and axially through said chamber, and tuyère means disposed in a pair of opposite divergent walls of said chamber for creating a cross draft through said moving fuel body.

15 13. In a heating plant, a fuel hopper, an elongated, stationary combustion chamber having approximately horizontal walls, said walls being gradually divergent from the entrance to the exit of said chamber, means for feeding fuel from said hopper to said chamber and for moving the body of fuel thus supplied horizontally and axially through said chamber, tuyère means disposed in a pair of opposite divergent walls of said chamber for creating a cross draft through said moving fuel body, and ash removal means disposed adjacent the exit end of said chamber into which the ashes overflow by gravity.

20 14. In a heating plant, a fuel supply, a combustion chamber, means for positively feeding fuel from said supply to and through said combustion chamber, inlet and outlet tuyères disposed in opposite walls of said chamber for creating a cross draft through the fuel, a furnace, and conduit means connecting said outlet tuyères with the interior of said furnace.

25 15. In a heating plant, the combination with a boiler of a combined stoker and combustion chamber detachably mounted in communication therewith, said combined stoker and chamber including means for positively feeding fuel to and maintaining a fuel bed of predetermined thickness in said chamber, means for creating a cross draft by applying air to one side of said fuel bed, and means for conducting the gaseous products of combustion from the opposite side of said chamber to the interior of said boiler.

30 16. In a heating plant, the combination with a boiler of a combined stoker and combustion chamber detachably mounted in communication therewith, said combined stoker and chamber including a fuel hopper, a combustion chamber laterally disposed with respect to said hopper and having gradually divergent walls from the entrance to the exit thereof, means for positively feeding fuel from said hopper to said chamber and for moving therethrough the body of fuel thus supplied, tuyères in one of said divergent walls for supplying air to the fuel bed, tuyères in the opposite divergent wall for exhausting the products of combustion from said chamber, and conduit means connecting said exhaust tuyères with the interior of said boiler.

35 17. In combination, a boiler, a combustion chamber exterior of said boiler, conduit means for conducting the gaseous products of combustion from said chamber to the interior of said boiler, said conduit means including means for directing said gaseous products at a relatively high velocity in a curvilinear path, and a dust trap wherein

- fine particles of dust and ash entrained in said gaseous products are deposited by centrifugal force.
17. In combination, a boiler, a combustion chamber exterior of said boiler, conduit means for conducting the gaseous products of combustion from said chamber to the ash pit of said boiler, a dust trap associated with said conduit means for collecting dust and fine ash blown through the combustion chamber, and baffle means at the delivery end of said conduit means for imparting to said gaseous products of combustion a relatively high curvilinear velocity toward the bottom of said ash pit and thereby depositing therein additional quantities of dust and fine ash entrained in said gaseous products.
18. In an automatic stoker for solid fuels, a fuel hopper, a combustion chamber, and means for feeding fuel from said hopper to said chamber comprising a rotatable drum interposed between the exit of the fuel hopper and the entrance of the combustion chamber, a plurality of blades carried by said drum, means for rigidly extending said blades beyond the periphery of said drum at the exit of said hopper to engage the fuel and carry it to the entrance of said chamber, and means for positively withdrawing said blades within the periphery of said drum at the entrance of said chamber.
19. In an automatic stoker for solid fuels, a fuel hopper, a combustion chamber, and means for feeding fuel from said hopper to said combustion chamber comprising a rotatable drum interposed between the exit of the fuel hopper and the entrance of the combustion chamber, a plurality of blades pivotally mounted within said drum, a plurality of slots in the periphery of said drum through which said blades are adapted to reciprocate, a roller operatively associated with each blade, a cam adapted to be engaged by said rollers in succession and to force said blades outwardly through said slots and into engagement with the fuel when adjacent the exit of said hopper, said cam being oscillatable around a fixed pivot and balanced by a counterweight to permit a yielding extension of said blades, and a fixed cam adapted to be engaged by said rollers and to positively force said blades inwardly through said slots when adjacent the entrance of said chamber.
20. In an automatic stoker for solid fuels, a fuel hopper, a combustion chamber, and means for feeding fuel from said hopper to said chamber comprising a rotatable drum interposed between the exit of the fuel hopper and the entrance of the combustion chamber, a plurality of shafts journaled within said drum adjacent the periphery thereof, a lever rigidly secured to each of said shafts, a fuel feeding blade pivotally connected to each of said levers, an arm rigidly secured to each of said shafts, a roller mounted on each of said arms, a plurality of slots in the periphery of said drum through which said blades are adapted to reciprocate, a cam adapted to be engaged by said rollers and to force said blades outwardly through said slots and into engagement with the fuel when adjacent the exit of said hopper, said cam being oscillatable around a fixed pivot and balanced by a counterweight to permit a yielding extension of said blades, and a fixed cam adapted to be engaged by said rollers and to positively force said blades inwardly through said slots when adjacent the entrance of said chamber.
21. In an automatic stoker of the type embodying a combustion chamber, means for feeding fuel
- to said chamber, a constant speed motor, means for driving said fuel feeding means from said motor and a blower directly connected to said motor for supplying air to said combustion chamber, the combination of a housing for said blower having an opening therein to admit air to said blower, a cap member mounted adjacent said opening and movable with respect to said housing, the space between said cap and housing providing an air inlet passage to said blower, means for moving said cap relative to said housing to vary the amount of air supplied to said blower, means for varying the speed at which said fuel feeding means is driven by said motor, and means operatively connecting said last two mentioned means for movement together whereby the amount of air supplied by said blower to said combustion chamber is regulated in proportion to the amount of fuel fed thereto by said fuel feeding means.
22. In an automatic stoker, a combustion chamber, means for feeding fuel into the entrance of said chamber, means for removing ashes from the exit of said chamber, inlet and outlet tuyères in opposite sides of said chamber, means for supplying air under pressure to the inlet tuyères, an exhaust passage communicating with said outlet tuyères, and conduit means leading from said air supply means to points adjacent the entrance and exit of said combustion chamber whereby the air pressure is equalized on both sides thereof.
23. In an automatic stoker, a combustion chamber, a fuel supply passage at one end of said chamber, an ash discharge passage at the other end of said chamber, tuyères in opposite sides of said chamber intermediate said fuel supply and ash discharge passages, an air trunk connected with the tuyères in one of said sides of said chamber for producing a cross draft therein, an exhaust passage communicating with the tuyères in the opposite side of said chamber, and conduits leading from said air trunk into both said fuel supply and ash discharge passages whereby the escape of gaseous products of combustion through said passages is prevented.
24. A combined automatic stoker and furnace unit comprising a fuel hopper, a combustion chamber in communication therewith, means intermediate said hopper and said combustion chamber for positively feeding the fuel into and through said combustion chamber, inlet and outlet tuyères in opposite sides of said combustion chamber, a conduit for supplying air to said inlet tuyères and thence to said fuel bed in a direction transverse to the direction of movement of the fuel therein whereby a fuel bed of predetermined thickness is maintained, a conduit for leading the products of combustion from said outlet tuyères, a blower for forcing air through said tuyères and fuel bed, and a motor for driving said feeding means and said blower, all of said elements constituting a self-contained unit adapted to be mounted exteriorly of a boiler and to be detachably connected thereto.
25. A combined automatic stoker and furnace unit comprising a fuel hopper, a combustion chamber in communication therewith, means intermediate said hopper and said combustion chamber for positively feeding the fuel into and through said combustion chamber, inlet and outlet tuyères in opposite sides of said combustion chamber, a conduit for supplying air to said inlet tuyères and thence to said fuel bed in a direction transverse to the direction of movement of the fuel therein whereby a fuel bed of predetermined thickness is maintained, a conduit for leading the products of combustion from said outlet tuyères, a blower for forcing air through said tuyères and fuel bed, and a motor for driving said feeding means and said blower, all of said elements constituting a self-contained unit adapted to be mounted exteriorly of a boiler and to be detachably connected thereto.

5 fuel therein whereby a fuel bed of predetermined thickness is maintained, a conduit for leading the products of combustion from said outlet tuyères, a blower for forcing air through said tuyères and fuel bed, and means associated with said combustion chamber for removing ashes from the end 10 of said chamber, all of said elements constituting a self-contained unit adapted to be mounted exteriorly of a boiler and be detachably connected thereto.

15 26. A combined automatic stoker and furnace unit comprising a fuel hopper, a combustion chamber in communication therewith, means intermediate said hopper and said combustion chamber for positively feeding the fuel into and through said combustion chamber, inlet and outlet tuyères in opposite sides of said combustion chamber, a conduit for supplying air to said inlet tuyères and thence to said fuel bed in a direction 20 transverse to the direction of movement of the fuel therein whereby a fuel bed of predetermined thickness is maintained, a conduit for leading the products of combustion from said outlet tuyères, a blower for forcing air through said tuyères and fuel bed, means for agitating the fuel in said 25 hopper to prevent arching therein, and a motor for driving said fuel feeding means, said blower and said agitating means, all of said elements constituting a self-contained unit adapted to be mounted exteriorly of a boiler and be detachably connected thereto.

30 27. A combined automatic stoker and furnace comprising a fuel hopper, an elongated, stationary combustion chamber extending at an angle 35 to said hopper, means intermediate said hopper and combustion chamber for feeding fuel from said hopper to said combustion chamber and for positively moving the body of fuel therethrough, said feeding means and combustion chamber being so constructed and arranged as to continually 40

5 maintain said chamber full of fuel and thereby provide a burning zone of predetermined thickness, means for providing a cross-draft of air to one side of said combustion chamber substantially transverse to the direction of movement of the fuel body therethrough and to support combustion therein, and means for conducting the gaseous products of combustion from the opposite side of said combustion chamber.

10 28. In an automatic stoker, a fuel hopper, a combustion chamber laterally disposed with respect to said hopper, the walls of said chamber providing a burning zone of definite cross sectional area and volume, means for feeding fuel from said hopper to said combustion chamber and 15 for positively moving said fuel therethrough, the body of fuel thus supplied completely filling said combustion chamber and thereby constantly providing a fuel bed of predetermined thickness, and tuyères in the opposite walls of said combustion 20 chamber for supplying air thereto and withdrawing the gaseous products of combustion therefrom in a direction substantially transverse to the direction of movement of said body of fuel therethrough.

25 29. In an automatic stoker, a fuel supply, a combustion chamber the walls of which provide a burning zone of definite cross sectional area and volume, means for positively feeding fuel from said supply into said combustion chamber to maintain said chamber completely filled with fuel and for moving said fuel through said chamber, whereby a burning fuel bed of predetermined thickness is provided, and inlet and outlet tuyères 30 in opposite walls of said chamber for providing a draft which is throughout substantially at right angles to the direction of movement of said fuel therethrough.
